FRANK LINCOLN STINE, OF EAST ORANGE, NEW JERSEY, ASSIGNOR TO BELDING HEM-INWAY COMPANY, OF NEW YORK, N. Y., A CORPORATION OF CONNECTICUT

LOUD-SPEAKER

Application filed January 7, 1929. Serial No. 330,901.

This invention relates to loud speakers and has for its object to provide a loud speaker with a fabric which will give a clear tone with a full volume of sound.

5 Another object of the invention is to provide a loud speaker with a fabric having a silk face in which the gum of the silk is preferably present.

Still another object of the invention is to 10 provide a loud speaker with a fabric having one face of cotton, the other face being of silk in which the gum of the silk is preferably present.

Additional objects will appear in the following specification in which the preferred form of the invention is described.

In the drawings similar reference characters refer to similar parts in all the views, in which

20 Figure 1 is a front elevation showing a loud speaker provided with my improved fabric;

Figure 2 is a sectional view on the line 2—2 of Figure 1; and

Figure 3 is a transverse sectional view 25 showing the fabric.

Various fabrics have been used in the past in loud speakers but the desired results have been impossible under all conditions. In my loud speaker a fabric is employed which gives 30 unusually good results, both as to tone and as to sound volume. This fabric has a silk face, preferably containing the natural gum of the silk, and preferably the fabric has one face of cotton, the other face being of silk in 35 which the gum of the silk is present.

Silk and satin which are to be used in garments and for household purposes are customarily boiled or treated in some other way to remove the gum of the silk, this being necessary in order that the silk and satin may be employed for the purposes for which they have hitherto been used. In my loud speaker the gum of the silk is preferably retained in the fabric as it has been found that the 45 gum of the silk is important to obtain the best results.

While in the drawings a particular type of loud speaker is shown, it will be understood that any preferred type of loud speaker may 50 be employed. As shown in the drawings, the

loud speaker has a diaphragm frame 5 and an auxiliary diaphragm frame 6, my improved fabric being used in the large diaphragm 7 and also in the auxiliary diaphragm 8, the diaphragm 7 and the auxiliary diaphragm 8 being connected by the driving pin 9 in the customary manner, this driving pin 9 leading from the customary unit 10 which is preferably supported by means secured to the diaphragm frame 5.

As best shown in Figure 3 of the drawings, the diaphragms 7 or 8 are made from a fabric 11 preferably having a silk face 12 with the other face preferably of cotton 13. The gum of the silk is preferably retained in the silk face 12 of the fabric 11 as it has been found that the presence of the gum of the silk is important in the fabric in order to obtain the best results.

It is immaterial whether the fabric is used 70 as the diaphragm with its silk face on the inner side and the cotton face on the outer side or whether the silk face is on the outer side and the cotton face is on the inner side.

What I claim is:

1. A loud speaker having a frame and a fabric secured to the frame, the fabric having one face of cotton and the other face of silk.

2. A loud speaker having a frame and a 80 fabric secured to the frame, the fabric having a silk face in which the gum of the silk is present.

3. A loud speaker having a frame and a fabric secured to the frame, the fabric having one face of cotton and the other face of silk in which the gum of the silk is present.

4. A loud speaker fabric having a silk face in which the gum of the silk is present.

5. A loud speaker having a frame and a 90 fabric secured to the frame and constituting a diaphragm, the fabric having one face of silk and the other face of another material.

FRANK LINCOLN STINE.
